UNITED STATES PATENT OFFICE

92,260

DESIGN FOR A LAMP SHADE

Charles F. Lamont, Los Angeles, Calif.

Application March 8, 1933, Serial No. 47,418

Term of patent 7 years

To all whom it may concern:

Be it known, that I, CHARLES F. LAMONT, a citizen of the United States, residing at Los Angeles, in the county of Los Angeles and State of California, have invented a new, original, and ornamental Design for Lamp Shades, of which the following is a specification, reference being had to the accompanying drawing, forming part thereof.

I claim:

The ornamental design for a lamp shade, substantially as shown and described.
In testimony whereof I affix my signature.

CHARLES F. LAMONT.
